H. TOBIAS

TOBACCO LATH HOLDER

Filed Aug. 9, 1924

Inventor
Henry Tobias.

UNITED STATES PATENT OFFICE.

HENRY TOBIAS, OF VIROQUA, WISCONSIN.

TOBACCO-LATH HOLDER.

Application filed August 9, 1924. Serial No. 731,182.

To all whom it may concern:

Be it known that HENRY TOBIAS, a citizen of the United States, residing at Viroqua, in the county of Vernon and State of Wisconsin, has invented certain new and useful Improvements in Tobacco-Lath Holders, of which the following is a specification.

This invention relates to an improved tobacco lath holder and the principal object thereof is to provide a holder in which the lath may be readily inserted or removed, and in which there are no positive fastening or securing means, the sole holding means being of a frictional character.

15 A further object is the provision of a holder having means for angularly and vertically adjusting the holder on the supporting bar of the spear horse.

With these and other objects in view, my 20 invention consists in the novel features of construction, combination and arrangement of parts as will be hereinafter referred to and more particularly pointed out in the specification and claims.

25 Referring to the drawing wherein for the purpose of illustration is shown the preferred embodiment of my invention,—

Figure 1 is a side plan view of the lath holder mounted on a supporting bar;

30 Figure 2 is a top plan view thereof;

Figure 3 is a longitudinal sectional view on the line 3—3 of Figure 1; and

Figure 4 is a vertical sectional view on the line 4—4 of Figure 1.

35 With particular reference to the drawing by numerals of reference, 2 designates a bar which is known in the art as a part of a spear horse and is adapted for the purpose of supporting the device which forms the 40 basis for the present invention.

The lath holder comprises a metal casting or stamping including a base plate 4 which is rhomboidal in plan, the sides of which describe a parallelogram. The device as a 45 whole is supported upon the bar 2 through the medium of a bolt 5 passing through one corner of the plate 4 and a bolt 6 passing through an arcuate slot 8 in the diagonally opposite corner, this latter construction being designed to permit angular adjustment of the plate upon the bar 2 with the bolt 5 as an axis. When properly adjusted, nuts on the bolts 5 and 6 are turned down to maintain the bar and plate relatively fixed.

55 The plate 4 is formed on the outer side with a housing 9 extending at an oblique

angle to the horizontal, said housing being either cast or struck down from one plane of the body of the plate 4 in the process of production. The housing is generally oblong 60 in plan and includes a top wall 10, side walls 11 and an end wall 12, the opposite end being left open as at 22 to provide for the entrance of a tobacco lath 14.

The top wall 10 is provided with a central 65 longitudinal slot 16 and adjacent each end, a plurality of transverse webs or bridges 18 and 19 respectively, said webs being outwardly offset from the plane of the wall 10. Supported and confined at one end upon one 70 end of the top wall 10, by means of a rivet 20, is a steel leaf spring 21, the longitudinally intermediate portion of which is bowed inwardly as at 24, while the free end 25 lies between the bridges or webs 18 and a 75 similar transverse web 26 extending across the longitudinal slot 16 in the plane of the top wall 10.

In practice, the bar 2 of the spear horse is usually maintained at an inclination as 80 shown in Figure 1, and the sides of the plate 4 parallel therewith. In this position, the housing is maintained substantially horizontal, although being capable of being swung upwardly or downwardly on the bolt 5 to vary the angular position of the lath 85 with respect to the horizontal. As the use of such a device as herein described is well known in the art, it is necessary only to state that the lath 14 is inserted in the housing 9 through the opening 22, and frictionally held by the leaf spring 21, while at the same time, the lath may be readily removed. During insertion or removal of the lath with respect to the housing, the spring is free to 90 move at its unrestrained end between the webs 18 and 26.

From the foregoing description of the construction of my improved device, it will be seen that I have provided a simple, inexpensive and efficient means for carrying out the objects of the invention, and while I have particularly described the elements best adapted to perform the functions set forth, it is obvious that various changes in 100 form, proportion, and in the minor details of construction may be resorted to, without departing from the spirit or sacrificing any of the principles of the invention.

Having thus described my invention, what 110 I claim is:—

1. A device of the class described, compris-

ing a metal base plate, rhomboidal in plan, a raised lath receiving housing formed in one face of said base plate, a leaf spring having a bowed portion extending within 5 and longitudinally of said housing one end of said spring being unrestrained.

2. A device as described comprising a plate, the sides of which describe a parallelogram, a housing formed in one face 10 thereof and extending at an angle to the longitudinal center of said plate, said housing having a longitudinal slot in its front wall, a leaf spring disposed in said slot and having a bowed portion extending within said 15 housing, means for fixedly supporting one end of said spring, and means for freely supporting the other end of said spring.

3. A device as described comprising a base plate the sides of which describe a parallelogram, a housing extending laterally from 20 one face thereof, said housing including a top wall, side walls and one end wall and said housing having an opening at the other end, said top wall being provided with a central

longitudinal slot, a spring disposed within 25 said slot and having a central longitudinally bowed portion extending within said housing, a fastening means for securing one end of said spring to one end of said top wall, and means for freely supporting and 30 guiding the other end of said leaf spring.

4. In a device of the character described, a metallic base plate having an elongated housing formed laterally of one face thereof, 35 fastening means at one corner of said plate, an arcuate slot formed in the obliquely opposite corner of said plate, said housing being formed with a longitudinal central slot in the top wall thereof, a leaf spring disposed within said slot and having a bowed 40 portion extending within said housing, means for rigidly securing one end of said spring, and means comprising a plurality of transverse webs extending across the inner 45 end of said slot for supporting and guiding the free end of said spring.

In testimony whereof I affix my signature.
HENRY TOBIAS.
